UNITED STATES PATENT OFFICE.

EMIL RUDBERG, OF DULUTH, MINNESOTA, ASSIGNOR OF ONE-THIRD TO KNUTE W. BERGMAN AND ONE-SIXTH TO AXEL J. FRANSON, BOTH OF DULUTH, MINNESOTA.

STORM-SASH FASTENER.

Application filed May 2, 1925. Serial No. 27,398.

This invention relates to window sash supports and has special reference to such a device particularly adapted for use in connection with storm sash on common house windows.

The principal object is to provide a more efficient and practical device of the character described.

Another object is to provide means whereby the support may be released or unlocked when desired in the event of the storm sash becoming abnormally fixed or stuck in closed position.

Other objects and advantages of the invention will appear in the further description thereof.

Referring now to the accompanying drawings, forming part of this application, and in which like reference characters indicate like parts:

Figure 1 is a vertical section of the lower portion of an ordinary window with a storm sash applied thereto and one of the improved fasteners;

Figure 2 is a somewhat similar view slightly reduced showing the storm sash open;

Figure 3 is an enlarged elevation of the lower adjustable end of the fastener; and

Figure 4 is a perspective view of one of the attaching brackets of the fastener.

1 represents the lower glazed sash of a common window and 2 the upper sash, while 3 represents the storm sash which is swingingly hinged at its upper end as is common in such devices, and 4 is the sill of the window frame.

I am aware that devices have been made which so unite the storm sash with the window sash that the former is automatically opened and closed by the opening and closing of the window sash. However certain novel features of my present invention will appear as follows; to wit: the bar 5 is pivotally united as at 6 to the storm sash 3 substantially the length of the bar above the lower end of the sash and the opposite end of the bar 5 is pivotally united in a similar manner as at 7 to the lower corner of the window sash 1, it being understood that there are usually 2 of such bars on each window. However it will be noted that my improved bar is not straight but is bent at

a considerable angle as at 8 so that the upper end lies parallel with the closed storm sash 55 while the lower portion extends diagonally across the space beneath the upper sash 2 of the window to the pivotal point 7, where it is attached to the lower sash 1.

The pivotal connection 7 is accomplished 60 by the lower end of the bar being provided with a notched hole 9, this hole or notch being open towards the sash 1 and cooperatively engageable about the pivot or pin 7 with the similarly shaped member 10 pivotally 65 mounted as at 11 upon the bar 5. The opposite end of the member 10 is provided with a slightly inwardly projecting lip or tit 12 which when the member 10 is aligned with the bar 5 registers within a suitable depression indicated at 13 in said bar, thus normally holding the member 10 and the bar 5 aligned in such a manner as to result in said bar maintaining normally a pivotal connection with the sash as previously stated. 70

Now in the event of the storm sash 3 becoming stuck as by sleet or otherwise to the window frame and a person wishing to open the window sash 1 he would ordinarily be barred from doing so regardless of whether 80 it was desired to open the storm sash or not. In such an event it is obvious that all that is necessary to free the inner lower sash from such locked condition would be to release the upper sash 2 and let it drop or bring same 85 down forcibly upon the inclined portion of the bar 5 which will thrust same outwardly to the position shown in dotted lines Fig. 1, thus automatically releasing the lower 90 pivotal connection of the bar in the manner illustrated, and if the upper sash is further forced downwardly it is apparent that the elbows in the bars 5 would force the sash 3 outwardly if so desired or after raising the inner sash which had thus been freed the 95 outer storm sash could be readily broken loose by hand, and the normal connection of the bar with the two sashes be again restored.

A preferred form of pivotal bracket is illustrated at 14, though other forms of same 100 may be employed as desired.

From the foregoing it is apparent that I have provided simple means for making a practical connection between the outer and inner sash to provide against abnormal sticking of the former, together with the ad-

vantage of the two being operated in unison as desired.

Having thus described my invention, what I claim and desire to secure by Letters Patent, is:

1. A fastener for a hinged outer sash for double windows, comprising a rod pivotally united at one end to the hinged sash and at the opposite end adjustably united to the lowermost double sash, and means whereby the lowering of the upper sash may be made

to disconnect the lower sash from the hinged sash.

2. The combination with a storm sash for a double sash window, of a rod cooperatively 15 adjustably uniting the storm sash with the lower sash of the window, said rod being selectively cooperative with the upper sash of the window.

In testimony whereof I hereunto affix my 20 signature.

EMIL RUDBERG.
